US00D625284S

(12) **United States Design Patent**
Cha

(10) **Patent No.:** **US D625,284 S**
(45) **Date of Patent:** **** Oct. 12, 2010**

(54) **MOBILE PHONE**

(75) Inventor: **Yong Duk Cha**, Gyeonggi-do (KR)

(73) Assignee: **LG Electronics Inc.**, Seoul (KR)

(**) Term: **14 Years**

(21) Appl. No.: **29/345,258**

(22) Filed: **Oct. 13, 2009**

(30) **Foreign Application Priority Data**

Apr. 14, 2009 (KR) 30-2009-0015841

(51) **LOC (9) Cl.** **14-03**

(52) **U.S. Cl.** ..... **D14/138 AB; D14/138 R**

(58) **Field of Classification Search** ..... D14/138 AB, D14/138 R, 138 AD, 138 G, 341-347, 203.4, D14/203.7, 203.2, 191; 455/575.3, 575.1, 455/556.2; 379/433.11, 433.13; D21/517; D18/7
